Inventor.

J. W. Rist.

UNITED STATES PATENT OFFICE.

J. W. RIST, OF ROCHESTER, N. Y., ASSIGNOR TO HIMSELF AND JOHN A. GUILE; SAID JOHN A. GUILE ASSIGNOR TO IRA A. HEBBARD, OF SAME PLACE.

IMPROVEMENT IN REGISTERS FOR KNITTING-MACHINES.

Specification forming part of Letters Patent No. **82,555**, dated September 29, 1868; antedated September 24, 1868.

To all whom it may concern:

Be it known that I, J. W. RIST, of Rochester, in the county of Monroe and State of New York, have invented a new and useful Count-Register for Knitting-Machines; and I do hereby declare that the following is a full, clear, and exact description thereof, reference being had to the accompanying drawing, making part of this specification, in which—

Figure 1 is a top view or plan of my invention, a small portion of the dial D being broken away, so as to show a portion of the ratchet-wheels W and w. Fig. 2 is an inverted view of the same, showing a portion of the ratchet-wheel W broken away, so as to expose the wheel w. Fig. 3 is a transverse section, taken in the plane of the line o in Figs. 1 and 2.

Like letters indicate like parts in all the figures.

This invention relates more especially to that class of knitting-machines which are capable of narrowing or widening; and it consists, mainly, in the employment or use of a suitable device for registering the "count," or the number of rounds the machine is run to form the different parts or sections of the stocking, or whatever is being knit, whereby the operator is entirely relieved from the perplexing task of keeping these counts mentally, and avoids entirely the annoyances consequent upon miscounts or mistakes.

To enable others to make and use my invention, I will describe its construction and operation.

The bed-plate B may be made of any suitable material, and is perforated to receive the hand-stud s, and also for that of the hand h'. This plate may be cast, and, if desired, provided with a raised rim or flange on the dial-side to receive a glass.

The ratchet-wheel W is raised from the plate B by a boss or hub cast upon the plate. The space between the plate and wheel should be sufficient to permit the free action of the wheel w. There may be a spherical steadyng-collar, C, placed between the clamping-nut E and the wheel W.

The nut E may be provided with a set-screw, a, which is screwed down firmly against the

end of the hand-stud s, so as to act as a jam-nut; or a jam-nut may be used, if desired.

The object of securing the adjustment of the clamping-nut E upon the stud s is that the hand h may be turned backward without unscrewing, when it is desired to set the hand h from any point where the machine may have been stopped back to its present position, as shown in Fig. 1.

The primary ratchet-wheel W has one hundred teeth, and the stroke of the driving-spring b is limited by the U-shaped guard d, between the sides or arms of which a spur from the end of the spring projects.

The pawl f is to prevent the wheel W from being turned backward by the spring b on its return stroke. The pawl e is applied to the secondary wheel w for a similar purpose.

There is a dial, D, Fig. 1, having one hundred divisions in its outer circle. D' has ten divisions, for the ten teeth of the secondary wheel w. It will be seen that either or both of these wheels may be made with a greater or less number of divisions, if desired.

The register, as herein shown, is designed more especially for the Lamb knitting-machine, and it is arranged to be attached to the left-hand end of the bed-frame of the machine by suitable bolts through the holes g.

There is a tappet attached to the sliding frame of the machine in such a manner as to strike the driving-spring at k at each right-hand stroke or throw of the frame. This moves the hand forward one notch; therefore, when the machine makes one hundred full strokes or rounds the hand h will have made one revolution, the pin i will catch a tooth of the secondary wheel w and turn it one notch, and, there being two teeth in this wheel, when the primary wheel makes ten revolutions the hand h' will have made one.

When the operator has run off any desired number of rounds, the primary hand h may be turned forward to its starting-point for a new count by means of the set-screw E, and the hand h' may be adjusted to its starting-point by vibrating the spring y, which may be done by a finger of the left hand.

The absolute necessity of keeping count

when running knitting-machines which are made to widen and narrow in order to make duplicates is well understood, and it is equally well understood that as a mental effort it is extremely difficult and very uncertain; whereas, with my invention, the count is faithfully and perfectly recorded. Therefore, by following a table of sizes and proportions for the different portions of a sock or other article, not only duplicates, but any number, may be made exactly alike.

The pin *i*, Fig. 3, projects from the inside face of wheel *W*, and nearly opposite to that of the hand *h*.

What I claim as my invention, and desire to secure by Letters Patent, is—

The arrangement of the driving-spring or latch *b*, double stop *d*, and ratchet-wheel *W*, in combination with the set-nut *E* and screw *a*, substantially in the manner and for the purposes set forth.

J. W. RIST.
